STRIP FEEDING MECHANISM

William A. Fletcher, Daleville, Ind., assignor to
 General Motors Corporation, Detroit, Mich., a
 corporation of Delaware

Application November 3, 1949, Serial No. 125,223

3 Claims. (Cl. 271—2.5)

1

This invention relates to feeding a strip of sheet metal in punch presses. It has been the practice to feed sheet metal by means of rolls which are driven by the crank shaft of the press through a one-way drive such as a one-way clutch. A sheet feeder of this type requires about one-half revolution of the press shaft for the feeding operation leaving the other half for die closing and opening to the extent required to permit feeding; and such feeder starts and stops its action relatively abruptly and requires the use of a brake to prevent over-travel, the maintenance of which is expensive.

An object of the invention is to provide a sheet metal feeding device which requires substantially less than one-half revolution of the press shaft to operate it so that greater die closing and opening time can be permitted and which will gradually accelerate the sheet from rest and which will gradually decelerate it to rest at the end of the feeding operation.

Further objects and advantages of the present invention will be apparent from the following description, reference being had to the accompanying drawings, wherein a preferred embodiment of the present invention is clearly shown.

In the drawings:

Fig. 1 is a front view of the feeding apparatus.

Fig. 2 is a side view looking in the direction of arrow 2 of Fig. 1.

Figs. 3 and 4 together form a plan view on a larger scale than Figs. 1 and 2 of the apparatus, the part in section at the left of Fig. 3 being on the line 3—3 of Fig. 1, and a fragmentary plan view of an attachment to the punch press crank shaft from which power is taken off for driving the feeding apparatus.

Fig. 5, drawn to the same scale as Figs. 3 and 4, is a fragmentary sectional view on line 5—5 of Fig. 1.

Fig. 6, drawn to the same scale as Figs. 1 and 2, is a fragmentary sectional view on line 6—6 of Fig. 5.

Fig. 7, drawn to the same scale as Figs. 3 and 4, is a fragmentary sectional view on line 7—7 of Fig. 2.

Fig. 8, drawn to the same scale as Fig. 7, is a fragmentary sectional view on line 8—8 of Fig. 2.

Fig. 9, drawn to the same scale as Fig. 1, is a view in the direction of arrow 9 of Fig. 1.

Fig. 10, drawn to the same scale as Fig. 9, is a sub-assembly of fixed and movable frame parts, the part in section being on line 10—10 of Fig. 11.

Fig. 11 is a view in the direction of arrow 11 of Fig. 10.

2

Fig. 12 is a sectional view on line 12—12 of Fig. 11.

Fig. 13 is a chart used in explaining the mode of operation of the feeding device.

5 The punch press is equipped with two similar feeding devices embodying the invention, one being used to push the sheet metal into the press and the other to pull it out. The feeding devices operate in synchronism. The drawings 10 show the feeding mechanism which pulls the sheet metal out from the press.

Referring to Figs. 3 and 4, 20 indicates a part 15 of the frame of the press as viewed from above it. The frame 20 provides vertically disposed machined surfaces 21 and 22 and supports vertical bars 23 which guide for vertical movement of frame 24 which can be vertically adjusted by means to be described.

Frame 24 provides vertically disposed machined 20 surfaces 25, 26, 27, 28, 29 and 29a and supports vertically disposed plates 30 in order to guide for vertical movement a frame (not shown) which carries a movable shear blade 31 (Fig. 5) cooperating with a shear blade 32 which is secured by

25 clamp bar 33 and screws 34 to a plate 35 which is supported by and movable with the frame 24. The function of blades 31, 32 is to cut into small 30 pieces the scrap or what is left of the strip S (Fig. 5) after the punches and dies of the press have punched out the required pieces which, for example, may be laminations for armature cores of dynamo electric machines. As shown in Fig. 1, the plate 35 is received by grooves 25a in frame 24 and is secured by screws 25b. As shown in

35 Figs. 2 and 9, the frame 24 has frontwardly extending portions of cylindrical shape 40 and 41 which are tied together by a rod 42 (Fig. 1) passing through a tube 43 and having threaded ends receiving nuts 44.

40 Sub-assembly A of the feeding device comprises a frame 50 secured to extension 40 by screws 51 (Fig. 3). Frame 50 provides a gear housing which is closed by caps 52 and 53 which support needle bearings 54 and 55 for a shaft 56 supported also by a needle bearing 57 carried by a bracket 58 attached to a bracket 59 (Fig. 2) which is attached to frame 50.

On shaft 56 there is loosely journaled a sprocket 60 connected by a chain 61 (Fig. 3) with a sprocket 62 attached to a support 63 attached to

45 a flange 64 which is provided by the crank shaft 65 of the punch press. It will be understood that parts 62—65 are located in the upper part of the punch press.

50 55 The sprocket 60 is connected with shaft 56 by

a one-turn clutch comprising a drum 70 connected with shaft 56 by a key 71 and carrying a dog 72 adapted to be received by a notch 73 of the sprocket 60. The dog is urged into this notch by a spring 74 retained by a ring 75 which screws 76 secure to the drum 70.

To the drum 70 screws 77 secure a brake drum 78 adapted to be frictionally engaged by a brake band liner 79 (Fig. 8) secured to brake shoes 80 which are connected by a pin 81 and which are urged together by a spring 82 surrounding a screw 83 threaded into one of the brake shoes and passing through a plain hole in the other and carrying a washer 84, the spring 82 being confined between this washer and the adjacent brake shoe. The right brake shoe 80 (Fig. 8) is supported by a screw 85 threaded into the extension 40 of frame 24.

Referring to Figs. 2 and 8, the clutch dog 72 can be retracted from the notch 73 by the interposition of a wedge 90 provided by a clutch throwout lever 91 pivoted on a pin 92 supported by the bracket 59 and carrying a pin 93 received by a slot 94 in a yoke 95 provided by a piston rod 96 connected with a piston in a cylinder 97. While the punch press is operating, pressure fluid is being admitted continuously to the left end of cylinder 97 so that lever 91 is disengaged from the dog 72 so that the press will continuously drive the shaft 56. When the strip material being fed through the punch press is used up, the press is caused to stop; and, through the medium of the cylinder 97, the lever 91 is caused to move to clutch throwout position so that the feed mechanism will stop at the end of its cycle. The brake functions only to stop the shaft 56 (Fig. 3) when the clutch is disengaged. It has no particular function with respect to the feeding operation.

The sub-assembly unit B (Fig. 7) of the mechanism comprises a frame 100 with screws 101 attached to the extension 40 of frame 24. Frame 100 supports needle bearings 102 for a shaft 103 which extends through a seal 104 and a thrust bearing 105 and which is connected by keys 106 bearing 107 meshing with a bevel gear with a bevel gear 108 (Fig. 3) connected by a key 110 with shaft 56. Gear 107 is retained by a washer 111 (Fig. 6) which a screw 112 attaches to the shaft 103.

Shaft 103 has a head portion 113 (Fig. 7) having a hole 114 receiving needle bearings 115 for a shaft 116 having an integral pinion 117 meshing with a fixed ring gear 118 (Fig. 5) fixed to frame 100 by dowel pins 119 and screws 120. The pitch radius of the gear 118 is indicated by *c* and the pitch radius of the pinion 117 by *a*. For reasons to be described, radius *c* is four times radius *a*. Shaft 116 has an integral crank portion 121 whose axis is represented by line 121a (Fig. 6). The eccentricity of axis 121a relative to the axis 116a of shaft 116 is represented by the letter *b* in Fig. 7. A cover 122 is secured by screws 123 to frame 100.

Referring to Figs. 10-12, sub-assembly C of the mechanism comprises brackets 130 and 131 which are attached to frame 24 as shown in Figs. 2 and 9 respectively. These brackets support a rod 132 which passes through spacing washers 133 and which has threaded ends receiving nuts 134 which on being tightened clamp the washers against shoulders 135 of the rod. That portion of the rod 132 between the shoulders 135 provides for reception of bearings 136 which are press fitted into frame members 140 and 141 and a connecting tube 142 which is welded thereto.

Referring to Fig. 12, members 140 and 141, together, with bosses 144 and 145 welded thereto, support bearings 146 and 147 respectively for a rod 148 which supports a yoke 149 integral with a pitman 150 which, as shown in larger scale in Fig. 7, receives a needle bearing 151 journaled on crank 121. Referring to Fig. 12, the yoke 149 of pitman 150 receives a bushing 152 shown on a larger scale in Fig. 5. This bushing guides for sliding movement a rod 153 providing a spherical seat 154 for the spherical end 155 of a link 156 connected by a pin 157 with a jaw 158 or clamp adapted to cooperate with a jaw 159 for gripping the strip of sheet metal S as shown in Fig. 5. Jaw 158 is guided for vertical movement by bars 160 secured by screws 161a to plate 161. Springs 162 tend to urge the jaw 158 downwardly and such downward movement relative to plate 161 is limited by the flanges 160a of plates 160. Jaw 159 is attached by screws 163 to a bracket 164 attached to frame members 140 and 141 and providing a channel 165 through which the strip S can pass. To exclude dirt from the spherical surfaces 154 and 155, a flexible member 166 is retained by a spring 167 against the bushing 152 and by a spring 168 against a shoulder 153 of the link 156. The lower clamp 159 is urged toward the upper clamp 158 as shown in Fig. 5 by a spring 170 confined in a tube 171 attached by screws 172 to the yoke 149 and connected by screws 173 with a plate 174 threadedly receiving a screw 175 retained in adjusted position by a nut 176. Screw 175 has an integral disc 177 which confines spring 170 in a state of compression between said disc and the lower end of the rod 153.

As shown in Fig. 5, the pitman 150 is in an upper position causing the strip S to be gripped by the clamps 153 and 159. When the pitman 150 is caused to move counterclockwise about the pivot 148 in a manner to be described, the bushing 152 engages the shoulder 153a of the rod 153 and causes it to move downwardly against the action of spring 170. Pressure of the rod 153 on the link 156 being relieved, springs 162 effect separation of clamp 158 from the clamp 159 to the extent permitted by engagement of clamp 158 with the flanges 160a of plates 160. Further counterclockwise movement of pitman 150 causes separation of rod 153 from link 156.

Referring to Fig. 13, a circle 118p represents the pitch circle of the ring gear 118 whose center is represented by point 103a' which represents the axis 103a (Fig. 5) of shaft 103 (Fig. 7). Circle 117p represents the pitch circle of the pinion 117. As stated before the radius of circle 118p is represented by a small letter *c* and the radius of circle 117p by the small letter *a*. The dot 116a' represents the center line 116a of shaft 116. Considering circle 117p as a disc rolling on the circle 118p, points at or within the boundary of this disc will generate what are known as prolate hypotrocoids. The polar equation for the prolate hypotrocoid shown in Fig. 13 in which *x* is the distance along a straight line from the center 103a' to the generating point, *u* is the angle in radians of that line with respect to a 45° diagonal through point 103a' and *b* is the distance from the center 116a' of the disc 117p to the generating point. Obviously, if *b* equals zero the center 116a' will generate a circle I regardless of the relation between *c* and *a*. When *c* equals 4*a* and *b* equals *a*, which means that the generated point lies on circle 117p, the symmetrical figure II will be generated. Obviously, other forms 75 of prolate hypotrocoids will be generated de-

pending upon the relation of values b to a , it being understood that b is less than a because, if greater than a , a curtate hypotrochoid would be generated.

For purpose of the present invention, it is desirable to obtain vertical upward movement of the clamp 158 (Fig. 5) to grip the strip S followed by horizontal movement for feeding purposes followed by downward vertical movement to retract the clamp 158 and followed by horizontal movement in the reverse direction to return the mechanism to initial position. I have found that when value b is substantially .36a, during one revolution of shaft 103 the axis of crank 121 represented by point 121a' in Figs. 5 and 13 will describe the prolate hypotrochoid figure, curve III, which is substantially a square having rounded corners. The mechanism is so arranged that when the clamps 158 and 159 are at mid-feeding stroke position, as shown in Fig. 5, the generating point or the end of axis 121a' will have moved on curve III to a position vertically above the axis above a point 103a' representing the end of the axis 103a of shaft 103 (Fig. 7). In other words, the axis 121a' of the crank 121 is so located as to be intersected in one position by a vertical line intersecting the axis 103a' of shaft 103 and the axis 116a of pinion 117 and at right angles to the path of movement of the sheet S. Therefore the locus of the positions of the axis 121a' are on the prolate hypotrochoid, curve III, two of whose parallel sides are parallel to the sheet S and two of whose sides are at right angles thereto.

Sprockets 60 and 62 (Fig. 3) have the same pitch diameter and gears 108 and 107 have the same pitch diameter. Therefore the center 116a' of shaft 116 will rotate once during each rotation of the punch press crank shaft. Point 116a' moves counterclockwise and describes circle I which can be used to represent one rotation of the punch press crank shaft. Horizontal position of the pitman is represented by line mn. When point 121a' is at P on curve III, the clamp 158 begins to press the strip S against the clamp 159. At Q the gripping action is sufficient for the starting of movement of the strip S to the left (Fig. 5). At Q the point 121a' starts moving horizontally as well as upwardly and the feeding of the strip begins slowly, the feeding speed increasing relatively slowly as the gripping action increases more rapidly. When point 121a' has reached R, the gripping action has reached such value as to permit more rapid increase of feeding speed. At point S the gripping pressure is at the maximum and the strip is being fed rapidly. At T deceleration of the strip begins. Feeding speed decreases as the crank axis 121a' rounds the corner to U, and then more rapidly between U and V. At V the gripping pressure begins to be relieved and at W the strip is entirely free.

The feed time is about one-third of a press shaft revolution and the die opening and closing time is about two-thirds. In the conventional stock feeding mechanisms, feed time is about one-half of a press shaft revolution. It is desirable to reduce feeding time especially for presses operating a plurality of punches which clear the dies at different elevations. By the present invention feeding time has been reduced and jerking of the stock has been eliminated.

The foregoing is a description of the stock feeder at the exit of the punch press. At the entrance to the punch press, there may be located a stock feeder which is constructed like the

one described with the exception that its supporting frame does not provide for guidance of a scrap cutter. It would have a shaft 56' (Fig. 3) corresponding to shaft 56 and connected therewith by coupling members 200 and 201. The two feeding mechanisms operate in synchronism.

The frames which support the two feeding mechanisms are vertically adjustable because, when the dies are ground to sharpen them, the elevations of the upper surfaces of the dies are lowered. Therefore, it is necessary to lower the frames which support the feeding mechanisms. Frame 24 is lowered by the turning of screws 199 (Fig. 5) threaded through bosses 191 provided by the press frame and receiving flat surfaces 192 provided by the extensions 40 and 41 of frame 24.

While the embodiment of the present invention as herein disclosed, constitutes a preferred form, it is to be understood that other forms might be adopted.

What is claimed is as follows:

1. A mechanism for use with a shaft operated punch press for moving a metal sheet in a substantially straight path, said mechanism comprising a shaft adapted to be connected with the press shaft as to rotate at the same speed and having its axis parallel to the sheet and at right angles to its path of movement, a fixed internal ring gear concentric with the mechanism shaft, a pinion having a pitch radius of one-fourth the pitch radius of the ring gear supported by the shaft for orbital movement about the axis thereof while meshing with the ring gear, a crank carried by the pinion and having its axis parallel to the pinion axis spaced from it a distance of about .36 the radius of the pinion and so located that, in a position of the pinion when its axis lies in a plane containing the center of the ring gear and located at right angles to the path of movement of the sheet material, said plane will contain the axis of the crank whereby, during a revolution of the shaft, the axis of the crank describes a prolate hypotrochoid figure which is substantially a square with rounded corners, two straight sides of the figure being parallel to said path of movement and two straight sides being at right angles to said path of movement, grippers located adjacent opposite sides of the metal sheet, one gripper being movable relative to the other, a frame supporting the grippers for movement in said path, a link connecting the crank with the frame, a spring normally ineffective to cause the movable gripper to advance toward the other gripper, and means operated by the link during movement of the crank in the parallel path defined by one of the first mentioned sides of the figure for conditioning the spring for urging the movable gripper toward the other gripper.

2. A mechanism for use with a shaft operated punch press for moving a metal sheet in a substantially straight path, said mechanism comprising a shaft adapted to be connected with the press shaft as to rotate at the same speed and having its axis parallel to the sheet and at right angles to its path of movement, a fixed internal ring gear concentric with the mechanism shaft, a pinion having a pitch radius of one-fourth the pitch radius of the ring gear supported by the shaft for orbital movement about the axis thereof while meshing with the ring gear, a crank carried by the pinion and having its axis parallel to the pinion axis spaced from it a distance of about .36 the radius of the pinion and so located that, in a position of the pinion when its axis lies in a plane containing the center of the ring gear and

located at right angles to the path of movement of the sheet material, said plane will contain the axis of the crank whereby, during a revolution of the shaft, the axis of the crank describes a prolate hypotrochoid figure which is substantially a square with rounded corners, two straight sides of the figure being parallel to said path of movement and two straight sides being at right angles to said path of movement, grippers located adjacent opposite sides of the metal sheet, one gripper being movable relative to the other, a frame supporting the grippers for movement in said path, a spring normally effective to separate the grippers, a compressible spring normally ineffective to advance the movable gripper toward the other gripper in opposition to the first spring, two abutment members between which the second spring is located, means transmitting motion from one abutment member to the movable gripper and a link which connects the crank with the frame and which supports the other abutment member, said second spring being compressed sufficiently to cause the movable gripper to move toward the other gripper during movement of the crank in the parallel path defined by one of the first mentioned sides of the figure.

3. A mechanism for use with a shaft operated punch press for moving a metal sheet in a substantially straight path, said mechanism comprising a shaft adapted to be connected with the press shaft as to rotate at the same speed and having its axis parallel to the sheet and at right angles to its path of movement, a fixed internal ring gear concentric with the mechanism shaft, a pinion having a pitch radius of one-fourth the pitch radius of the ring gear supported by the shaft for orbital movement about the axis thereof while meshing with the ring gear, a crank carried by the pinion and having its axis parallel to the pinion axis spaced from it a distance of about .36 the radius of the pinion and so located that, in a position of the pinion when its axis lies in

5 a plane containing the center of the ring gear and located at right angles to the path of movement of the sheet material, said plane will contain the axis of the crank whereby, during a revolution of the shaft, the axis of the crank describes a prolate hypotrochoid figure which is substantially a square with rounded corners, two straight sides of the figure being parallel to said path of movement and two straight sides being at right angles to said path of movement, a frame which extends generally at right angles to the plane of the sheet, a sheet gripper fixed at one end of the frame on one side of the sheet and a gripper on the other side of the sheet and supported by the frame for movement toward the fixed gripper, spring means for urging the movable gripper away from the fixed gripper, a pivot support for the frame at the end thereof remote from the grippers, a link pivotally connected with the crank and the frame, and means for transmitting motion yieldingly from the link to the movable gripper to move it against the sheet as the link swings toward the sheet.
